UNITED STATES PATENT OFFICE

PATRICK J. GRIFFIN, OF BOSTON, MASSACHUSETTS, ASSIGNOR OF ONE-HALF TO
EDWARD L. LOGAN, OF BOSTON, MASSACHUSETTS

MOORING

Application filed February 26, 1930. Serial No. 431,433.

This invention relates to mooring lighter than air craft and to mooring masts as well as to means providing terminal facilities for such craft.

5 Objects of the present invention are to provide improved means for mooring lighter than air craft; to provide a mooring which may be raised and lowered to facilitate landing and taking off of such craft; to provide 10 means for supporting the body of the craft for movement about the mooring and also for holding the body from upward movement; to provide improved means for accommodating passengers and for handling 15 freight at a mooring; to provide apparatus of this general class embodying means for indicating the lifting power of such craft; and also to provide apparatus of the class described having an improved construction and 20 arrangement of parts.

In the drawings:

Fig. 1 is a side elevation of apparatus for mooring air craft;

Fig. 2 is a top plan view of a portion of the 25 apparatus shown in Fig. 1;

Fig. 3 is a side elevation of one of the cradles for supporting the craft;

Fig. 4 is a transverse section through one 30 of the tracks showing a cradle in end elevation; and

Fig. 5 is a view of a detail of construction.

The apparatus selected for illustration comprises a framework 10 comprising suitable 35 columns 11 and bracing members 12 arranged in any approved manner for supporting a platform 13 at a suitable distance above the ground to provide for supporting an air craft in a position for movement about its mooring without danger of engagement with trees, 40 buildings or other objects upon the ground. A vertical hydraulic cylinder 14 is centrally disposed within the framework 10. A piston 16 is mounted within this cylinder and carries at its upper end an eye 17 which is connected to the piston by swivel connection 18. An enclosure 19 adapted to serve as a waiting 45 room is circular in outline and is disposed concentrically about the piston and cylinder, the latter extending through the roof of this enclosure. A landing platform or passenger

deck 21 is also supported by the platform 13 and extends preferably entirely around the waiting room 19. Disposed on the platform 13 concentrically about the piston and outside the landing deck are double tracks 22, 55 23 on which the cradles 24 are adapted to operate movably to support an air craft such as the dirigible 26. As shown more clearly in Figs. 3 and 4 the cradles 24 may be similar to railway trucks comprising axles 27 60 having flanged wheels 28 fast thereon with journals (not shown) disposed outside of the wheels. The trucks are provided with side frames 29 carrying journal boxes 31 which receive the journals. The truck body 65 32 is provided with a body bolster 33 which rests upon the truck bolster 34, the ends of the latter being supported upon springs 36 which are carried by the side frames 29 in the usual manner. Undergaff wheels 37 are 70 rotatably mounted upon a transverse shaft which is connected by means of a rod 39 to the body bolster 33. The wheels 37 operate in a T-shaped slot formed between the rails of each track by a pair of center rails 41 75 having inwardly directed upper flanges 42. Anchor irons 43 are secured at the ends of the body of each truck to receive lashing for holding the craft to the truck. Flexible lashing strips 44 are secured to the anchor irons 80 43. The adjacent ends of these strips are reduced in the form of tongues 46 which are adapted to be secured together by a buckle or other approved fastening device 47. Gauges 48 are supported by suspension elements 49 affixed to the strips 44 above the fastening device 47. Each gauge carries a hook 51 which is engageable with an eye 52 affixed to the lashing below the buckle 47.

In the operation of the apparatus the 90 plunger 16 is operated by controls 48 within the enclosure 19. When a dirigible for example is ready to be moored the plunger 16 is elevated above the platform 13 so that the nose of the dirigible may be secured to the eye 17 without danger of damage to the dirigible by unintentional contact with the platform 13 or other portions of the framework 10. Once the nose of the dirigible is secured in 95 this manner the piston 16 is lowered by fluid 100

delivered to the cylinder 14 thereby pulling the nose of the dirigible toward the platform 13. It will be seen that when the nose has been lowered in this manner the lashing strips 44 may be thrown over the body of the dirigible and secured together thereby securely lashing the dirigible to the movable cradles 44. It will also be evident that when supported in this manner a craft of this type is free to move about its mooring so as to lie in the wind and at the same time to be movably supported.

When the dirigible is about to take off the hooks 51 are connected to the eyes 52 and the fastening devices 47 are disconnected. It is then possible by reading the gauges 48 to ascertain whether the ship is trimmed properly to rise with the plunger 16. These gauges also enable an operator to know the speed at which the plunger 16 should move upwardly. In this way it is possible to avoid damage to the ship by having the tail shoot upwardly when the lashings are released or by raising the nose fast enough to drag the ship against some portion of the structure 10. When the readings of the gauges 48 are found to be satisfactory the hooks and eyes 51, 52 are disconnected and the plunger 16 is raised at the proper speed to keep the ship trimmed while it is being raised to a position well above the platform 13. After this it is necessary merely to disconnect the nose from the eye 17 to free the craft from its mooring.

35 I claim:

1. The combination with a mooring for the nose of an airship, of lashing strips adapted to be brought together about the body of the ship, releasable means for securing the lashing strips together, gauges, and means for interposing the gauges in the lashings for indicating the buoyancy of the ship.

2. The combination as set forth in claim 1, and movable means for supporting the ship, the lashings being affixed to the movable means.

3. Apparatus of the class described comprising a framework, a vertical power cylinder within the framework, a piston in the cylinder, a mooring connected to the piston, circular tracks on the framework and concentric with the mooring, trucks on the tracks for supporting a craft, and a passenger deck disposed within the tracks and approximately coplanar therewith.

4. Apparatus of the class described comprising a substantially horizontal platform disposed at an elevation well above the ground to be substantially clear of trees, buildings and like objects on the ground, a structural framework for supporting the platform in this position, a plunger movable vertically through the platform between a position in which the upper end of the plunger is spaced above the platform a distance ap-

proximately to align with the nose of a ship to be moored when in mooring position adjacent the platform and a higher position in which the ship may move freely about the platform, means within the framework for operating the plunger between these positions, circular tracks on the platform concentric about the plunger, wheeled cars on these tracks, undergaff wheels on the cars engageable with some of the tracks for restraining upward movement, and means for securing the forward portion of the body of the ship to be moored to said cars.

5. Apparatus of the class described comprising a substantially horizontal platform disposed at an elevation well above the ground to be substantially clear of trees, buildings and like objects on the ground, a structural framework for supporting the platform in this position, a plunger movable vertically through the platform between a position in which the upper end of the plunger is spaced above the platform a distance approximately to align with the nose of a ship to be moored when in mooring position adjacent the platform and a higher position in which the ship may move freely about the platform, means within the framework for operating the plunger between these positions, circular tracks on the platform concentric about the plunger, wheeled cars on these tracks, undergaff wheels on the cars engageable with some of the tracks for restraining upward movement, a waiting room on the platform extending about the plunger, and a passenger deck on the platform extending between the waiting room and the tracks, the passenger deck being substantially coplanar with the tracks.

Signed by me at Boston, Massachusetts, this 21st day of February, 1930.

PATRICK J. GRIFFIN.
